(57) **CLAIM**

The ornamental design for a battery charger for mobile device, as shown and described.

DESCRIPTION

FIG. 1 is a top view of a first embodiment of a battery charger for mobile device.

FIG. 2 is a back view of the battery charger for mobile device of FIG. 1 with the power plug folded.

FIG. 3 is a back perspective view of the battery charger for mobile device of FIG. 1 with the power plug extending outward.

FIG. 4 is a top perspective view of a second embodiment of the battery charger for mobile device with an alternative power plug on the back side.

FIG. 5 is a top view thereof.

FIG. 6 is an a perspective view thereof.

FIG. 7 is a bottom side view thereof.

FIG. 8 is a side view thereof.

FIG. 9 is a top view of a third embodiment of the battery charger for mobile device an alternative power plug folded.

FIG. 10 is a back view thereof.

FIG. 11 is a bottom side view thereof.

FIG. 12 is a front perspective view thereof.

FIG. 13 is a side view thereof.

FIG. 14 is a perspective view of the battery charger for mobile device with the power plugs protruding and with a USB connector plugged in; and,

FIG. 15 is a front view of the battery charger for mobile device with a USB connector plugged in.

Boken lines on the battery charger for mobile device and form no part of the claimed design. The broken lines showing a USB connector in FIGS. 14 and 15 depict environmental subject matter and form no part of the claimed design.

1 Claim, 5 Drawing Sheets
